United States Patent Office.

MOSES HAWKINS, OF BIRMINGHAM, CONNECTICUT.

Letters Patent No. 63,045, dated March 19, 1867.

IMPROVEMENT IN STEAM-ENGINE OIL-CUPS.

The Schedule referred to in these Letters Patent and making part of the same.

TO ALL WHOM IT MAY CONCERN:

Be it known that I, MOSES HAWKINS, of Birmingham, of the county of New Haven, in the State of Connecticut, have invented a new and useful Oil-Cup for Steam Engines; and I do hereby declare that the following is a full and exact description thereof, reference being had to the accompanying drawings, making part of this application.

My invention relates to a novel method of constructing an oil-cup for steam cylinders, and has for its object to effect the feeding in of the oil automatically by the action of steam, in a manner to be presently explained, and to this end my invention consists in a novel mode of constructing oil-cups, in which the lubricating material therein contained is lifted by condensed steam and allowed to flow over into and down through the steam tube into the cylinder, as hereinafter more fully described.

To enable those skilled in the art to make and use my invention, I will proceed to describe it more fully, referring by letters to the accompanying drawings, in which I have shown in vertical section one of my new oil-cups.

A is the body of the oil-cup, which may be made of any shape convenient to contain the oil or other lubricator, and the hollow stem or neck B of which is provided with a cock or valve, C. From the upper portion of the stem B (or bottom of cup A) extends upward, nearly to the top edge of cup A, a tube, D, the function of which will be presently explained. E is a cap or cover, which is screwed on the upper edge of cup A, as shown, and which is removed and replaced whenever it is necessary to replenish the lubricator. f is the waste-cock through which the cup A is emptied, as will be presently explained.

In the drawing, the cup A is illustrated as if about half exhausted of its full allowance of oil; the space lined with blue illustrating water, that lined with red, oil.

The operation of an oil-cup constructed as described may be thus explained: The stem B being secured to the steam engine in the ordinary manner, and the cock or valve C turned so as to cut off communication between the cylinder and cup A, the latter is filled with oil, (or other lubricating material,) and its lid E screwed on tight, and the cock f closed. To effect a supply of oil to the cylinder, the cock C is turned, as seen in the drawing, so as to admit steam into the oil-cup. The steam passes up through the central tube D, and escaping therefrom is allowed to condense in the body A, when it descends in the form of water to the bottom of the cup A, displacing a given amount of the oil, which rises and flows down the tube D into the cylinder. In this manner the cylinder is oiled as long as the oil lasts, and when the supply is exhausted, and the cup A becomes full of water, (condensed steam,) the cock C being closed, the waste-cock f is opened, the water drawn off, and the cup A refilled with oil. If tallow or other congealed or solidified grease be used the action of the steam will melt and feed in the same in the manner explained of the oil.

Having explained the construction and operation of my new oil-cup so that one skilled in the art can make and use the same, and being aware that oil-cups have been heretofore made in which the oil was fed in, by displacement effected by condensed steam, what I claim as new, and desire to secure by Letters Patent, is—

An oil-cup A, provided with a stand pipe D, extending up to near the cap E, and a water-cock f, the whole constructed and operating as described.

In testimony whereof I have hereunto set my hand and seal this 26th day of November, 1866.

MOSES HAWKINS. [SEAL.]
